UNITED STATES PATENT OFFICE.

WILLOUGHBY A. HENLEY, OF ALTUS, OKLAHOMA.

AEROPLANE.

1,237,039.

Specification of Letters Patent. Patented Aug. 14, 1917.

Application filed March 16, 1917. Serial No. 155,321.

To all whom it may concern:

Be it known that I, WILLOUGHBY A. HENLEY, a citizen of the United States, residing at Altus, in the county of Jackson and State 5 of Oklahoma, have invented new and useful Improvements in Aeroplanes, of which the following is a specification.

This invention relates to aeroplanes and has particular reference to means for automatically stabilizing the machine in flight, the stabilizing means operating both laterally and in a fore and aft direction to maintain the equilibrium of the machine both laterally and longitudinally while in actual 15 flight without any attention on the part of the aviator.

A further object of the invention is to provide stabilizing means which will not interfere with the manual control of the 20 stabilizing planes and horizontal rudder as when rising, descending or steering in any direction. The stabilizing apparatus hereinafter particularly described and illustrated in the drawings is of such a character 25 that it may be used in conjunction with an aeroplane of any type such as a monoplane, biplane or multiplane.

With the above and other objects in view, the invention consists in the novel construction, combination and arrangement of parts, hereinafter described, illustrated and claimed.

In the accompanying drawings:—

Figure 1 is a plan view of the machine 35 showing the stabilizing means in its applied relation thereto.

Fig. 2 is a vertical longitudinal section particularly illustrating the means for automatically controlling the horizontal rudder or fore and aft stabilizing plane.

Fig. 3 is a vertical transverse section on the line 3—3 of Fig. 1 particularly illustrating the lateral stabilizing means.

Fig. 4 is a diagrammatic perspective view 45 illustrating the complete stabilizing apparatus.

The aeroplane which may be of any desired type, is shown as comprising a main supporting plane 1, a tail frame or fuselage 50 2, and 3 a horizontal rudder forming the fore and aft stabilizing plane. The main supporting plane 1 has associated therewith and flexibly connected thereto lateral balancing or stabilizing planes 4, usually 55 termed ailerons.

The means for automatically operating

the fore and aft stabilizing plane or horizontal rudder 3, comprises a pendulum or two armed lever 5, the same being pivotally mounted at 6 between its ends on a pivot bearing, preferably of an antifriction type to insure the easy working of the lever 5. The lower end of the lever 5 carries a weight 7 of any suitable size which causes the lever 5 to automatically assume a vertical position irrespective of the fore and aft inclination of the machine while in flight. Fasted to the upper arm of the lever 5 is a flexible connection 8 such as a cable which extends from the lever 5 to a point in advance thereof where it passes around a guide 9 shown in the form of a pulley and then rearwardly where it passes from another guide 10 shown in the form of a pulley journaled on the upper end of a post or 75 standard 11, the latter extending both above and below the rear end of the tail frame or fuselage 2. The cable 8 is attached at its rear extremity to the trailing edge of the horizontal rudder as shown at 12. Another 80 flexible connection or cable 13 is attached at one end to the trailing edge of the horizontal rudder 3 and extends under a guiding pulley 14 journaled on the lower extremity of the post 11 and thence forwardly and upwardly where it is secured at its other end to the upper arm of the weighted lever 5.

If the machine assumes too steep an angle in climbing, the weight 7 moves rearwardly causing the upper arm of the lever to move in a forward direction and thereby pulling downwardly on the trailing edge of the horizontal rudder 3, while the other cable attached to said horizontal rudder and weighted lever is automatically slackened to admit of such movement of the horizontal rudder. When the machine dips too steeply, the weighted lever 5 swings in the opposite direction thereby raising the trailing edge of the horizontal rudder. Under either of the 100 conditions last named, the fore and aft equilibrium of the machine is automatically restored.

The means for automatically controlling the lateral stability of the machine, embodies 105 a second pendulum or weighted lever 15 which is pivotally mounted intermediate of its ends at 16 preferably on an antifriction bearing. The lever 15 carries a weight 17 of suitable size at its lower end causing it to 110 always assume and maintain a vertical position. A flexible connection or cable 18 is at-

tached at one end to the upper arm of the lever 15, extending therefrom, around a guide pulley 19, thence downwardly around a pulley 20 and thence to the trailing edge 5 of one of the ailerons 4 to which it is attached at 21. Another cable 22 is secured at one end to the trailing edge of said aileron 4 and extends upwardly therefrom around a guide pulley 23, then transversely of the 10 machine around another pulley 24 and then forwardly where it is attached at its extremity to the upper arm of the lever 15. Another cable 25 is likewise attached at one end to the upper arm of the lever 15 and ex- 15 tends downwardly around a guide pulley 26 and then downwardly around another guide pulley 27, thence laterally and upwardly where it is terminally attached at 28 to the trailing edge of the other aileron. Another 20 cable 29 has one end secured to the trailing edge of the last named aileron and extends upwardly over a guide pulley 30 thence transversely of the machine around another guide pulley 31 and then upwardly where it 25 is terminally attached to the upper arm of the weighted lever 15.

By reason of the arrangement of the lateral balancing connections just hereinabove described, when the weight 17 swings toward 30 the lower or depressed side of the machine, the trailing edge of the aileron at said side of the machine is depressed while the trailing edge of the aileron at the higher or elevated side of the machine is raised. This 35 causes a lifting of the lower side and a depression of the higher side of the machine, thereby restoring lateral equilibrium of the machine.

The guide pulleys 19, 23 and 31, are journaled upon the upper end of one of a pair of standards 32, the upper end of the other standard carrying the pulleys 24, 26 and 30. The pulley 20 is journaled upon the lower end of one of the standards 32, and the pulley 27 40 is journaled on the lower end of the other standard 32. Other guides or pulleys 33 are supported by the standards 32 and serve to direct the movements of the flexible connections or cables 8 and 13 which control the 45 horizontal rudder 3, the pulleys or guides 33 being arranged equidistantly from the center of the machine to provide for the necessary clearance or freedom of movement of the upper arm of the weighted lever 15. 50 From the foregoing description taken in connection with the accompanying drawings it will now be understood that one of the weighted levers automatically controls the flexible connections which in turn control the 55 horizontal rudder for the purpose of maintaining the fore and aft stability or 60

equilibrium of the machine. Another weighted lever automatically controls the connections which in turn control the lateral balancing planes or ailerons for automatically maintaining the lateral equilibrium of the machine. Thus both the fore and aft and lateral equilibrium of the machine are automatically taken care of without any attention on the part of the aviator. The 65 aviator may, however, by means of the usual manually controlled devices, overcome the action of the automatic controls whenever it is necessary to steer the machine in either an upward or downward direction or to one 70 side or the other. While I have referred to the flexible connections as consisting of cables, it will of course be understood that any form of flexible connection may be used that will accommodate itself to the movements 75 necessary to easily control the stabilizing planes.

I claim:—

In an aeroplane, the combination of a supporting surface, a weighted lever pivotally 85 mounted in relation thereto, lateral balancing planes whose trailing edges are capable of being moved upwardly and downwardly, flexible connections attached to said lever and to the trailing edges of said lateral bal- 90 ancing planes for elevating the trailing edges thereof, other flexible connections attached to said lever and to said lateral balancing planes and acting to depress the trailing edges there- 95 of, the arrangement of said flexible connec- tions being such that the trailing edge of one lateral balancing plane is elevated simultane- 100 ously with the depression of the trailing edge of the other lateral balancing plane, standards arranged at opposite sides of the longitudinal center of the machine and ex- 105 tends above and below the supporting surface, guiding means for said flexible connections supported by the upper and lower extremities of said standards, a second 110 weighted lever adapted to swing in a fore and aft direction and pivotally mounted in relation to said supporting surface, a fore and aft stabilizing plane, flexible connec- 115 tions extending from said second weighted lever to the trailing edge of said fore and aft stabilizing plane for raising and de- pressing the latter, and guiding means on said standards for directing the last named flexible connections, said guiding means being located in spaced relation to each other and equidistantly from the longitudinal center of the machine to provide clearance for the first named weighted lever.

In testimony whereof I affix my signature. 120

WILLOUGHBY A. HENLEY.
